UNITED STATES PATENT OFFICE.

FREDERICK H. HARMER, OF MILWAUKEE, WISCONSIN, ASSIGNOR TO ALLIS-CHALMERS COMPANY, OF MILWAUKEE, WISCONSIN, A CORPORATION OF NEW JERSEY.

VALVE.

No. 844,307.

Specification of Letters Patent.

Patented Feb. 12, 1907.

Application filed December 17, 1906. Serial No. 348,160.

To all whom it may concern:

Be it known that I, FREDERICK H. HARMER, a citizen of the United States, residing at Milwaukee, in the county of Milwaukee and State of Wisconsin, have invented a certain new and useful Valve, of which the following is a specification.

This invention relates to valves for controlling the flow of fluids under pressure; and the purpose of the invention is to provide a cheap compact valve which consists of but few parts and which provides ample bearing-surfaces where the movable parts are subjected to frictional contact, so that the parts may remain appreciably true to size for a long period, so that the valve will retain its usefulness for a long period without attention or the replacing of parts.

In the drawings which accompany this specification and form a part thereof and on which the same reference characters are used to designate the same elements wherever they may appear in the several views, Figure 1 represents a vertical elevation of a valve embodying this invention, parts of the same being shown in section. Fig. 2 represents a plan view of the seat member, and Fig. 3 represents a perspective view of the seat member with the valve in position thereon.

Referring to the drawings, the numeral 1 represents a member adapted to be secured to any suitable support by the perforated lugs 2, through the perforations of which are adapted to be passed screws or bolts. The member 1 is provided with passages or ports 3, 4, and 5, with which, respectively, are adapted to be connected the pipes 6, 7, and 8. The ports 3, 4, and 5 extend completely through said member 1 and are adapted to communicate with ports 9, 10, and 11 in a seat member 12, which is adapted to be seated upon the member 1 and make a fluid-tight contact therewith, either by careful fitting of the adjacent parts of said members or by washers or packing material, as 13. The ports 9, 10, and 11 extend through the seat member 12. Seated upon the seat member 12 is the casing 14, which is in the form of a hollow shell and is secured against the seat member 12 by a fluid-tight joint either by the parts being accurately fitted together or by the use of washers or any suitable packing material. Casing 14 is provided with a projection 15, which is bored to receive a ro-

table stem 16, which is fitted fluid-tight into 55 said bore in any suitable manner, as by grinding a projection 17 on said stem in engagement with a part 18 of said bore. To the outstanding end of the stem 16 is secured the operating-handle 19, provided with a 60 spring-backed catch 20, which is adapted to coöperate with a stationary part, preferably of the projection 15, to retain the handle 19 and the valve which it controls in any predetermined position.

The seat member 12 is provided within the cavity of the casing 14 with a valve-seat 21, upon which the valve 22 is adapted to be reciprocated, suitable guides 23 and 24 being provided between which said valve slides and 70 by which its motion in a right line is assured. This valve 22 is essentially of the common D-slide form having a cavity 25 in one surface, which, however, does not open through the sides of said valve, as clearly shown by Figs. 75 1 and 3, the length of this cavity being such that when the valve is moved to its proper position over ports 10 and 11 said ports will be placed in communication each with the other through said cavity 25. The surface 80 of said valve opposite that containing cavity 25 is provided with the projections 26 and 27, between which is adapted to reciprocate the slide block 28, the line of movement of said block being at right angles to the line of 85 movement of the valve 22. This block 28 is provided with an aperture, preferably cylindrical in form, in which is adapted to be seated a cylindrical pin 29, secured to the stem 16 and eccentric to the axis of said stem. 90

The ports 10 and 11 open through the seat member 12 directly in the line of travel of the valve 22 and are adapted to be entirely covered by said valve, so that there is no communication between said ports and the interior of the casing 14, this arrangement being clearly shown by Figs. 1, 2, and 3 of the drawings.

The port 9 in the seat member 12 does not open through said member in line with the 100 travel of the valve 22; but in the specific instance shown it is branched within said seat member 12, the two branches 30 and 31 opening within the casing 14 on opposite sides of the seat for the valve 22.

The numerals 32 and 33 designate lugs upon the seat member 12, which lugs are apertured and are adapted to align with simi-

lar apertured lugs, as 34, upon the casing 14 and similar lugs upon the member 1, bolts 35 being passed through the apertures of the several lugs to retain the parts in their assembled relation.

The numeral 40 represents a screw which closes a screw-threaded aperture, through which oil may be introduced for lubricating the movable parts of the valve.

10 The valve-seat face of the seat member 12 is depressed at the periphery, as at 41, in order that the ends of the valve at its limits of travel may project thereover, and thus prevent the valve wearing into its seat and forming shoulders.

15 The port 11, where it opens through the seat of the valve 22, is preferably of triangular shape, as clearly shown by Figs. 2 and 3, so that the aperture of said port can be controlled with great accuracy and certainty.

20 While this valve is adapted to control the flow of any fluid under pressure, it is especially adapted to control the flow of air under pressure in order to admit it to a motor and then to permit it to exhaust therefrom; and in this connection it may be stated that this valve is well adapted for use as an engineer's valve on vehicles and trains where brakes are operated by air under pressure.

25 30 The operation of the device is as follows: The pipe 6 being in communication with a fluid under pressure the fluid under pressure passes by way of pipe 6, port 9, and branches 30 and 31 to the interior of the casing 14, and 35 with the position of the valve as shown by Fig. 1 it would also pass through the port 11 and pipe 8 to the motor or brake-cylinder until the pressures would be equalized throughout the communicating parts of the system.

40 45 If now the valve be moved to the left, (see Fig. 1,) so as to bring port 11 into communication with port 10 through the cavity 25, then the fluid under pressure in the motor or

brake cylinder can exhaust through port 11, cavity 25, and port 10, or if the apparatus is used in some other relation the fluid can pass from port 11 to port 10, and to some other point of use through pipe 7.

It will be noticed that the interior of the casing 14 being filled with the fluid under pressure the valve 22 is held to its seat by the pressure of said fluid, thus preventing the necessity of springs or other devices for keeping it on its seat.

What I claim is—

1. The combination with a valve-seat provided with ports, of a valve member resting against said seat, said seat being provided with guides to restrain the movement of said valve member, said valve member being provided with guides disposed at an angle with respect to the guides upon said valve-seat, a stem provided with a pin eccentric to the axis thereof, a block adapted to move between the guides on said valve member, said block being provided with an aperture adapted to receive said pin.

2. The combination with a valve-seat provided with ports, of a rectangular valve member adapted to control said ports, guides for compelling said valve member to move in a right line, a valve-stem provided with a pin disposed eccentrically to the axis of said stem, a rectangular block provided with an aperture adapted to receive said pin, said valve member being provided with guides disposed at right angles with respect to the guides on the valve-seat, said guides being adapted to restrain the movement of said block to a right line.

In testimony whereof I affix my signature in the presence of two witnesses.

FREDERICK H. HARMER.
